US00D663776S

(12) United States Design Patent
Lira-Nunez et al.

(10) Patent No.: US D663,776 S
(45) Date of Patent:  Jul. 17, 2012

(54) ERASER AND MARKER HOLDER

(75) Inventors: Carmen Okuku Lira-Nunez, Downers Grove, IL (US); Allison Rose Dunphy, Cincinnati, OH (US); Katherine Joan Radville, La Grange Park, IL (US)

(73) Assignee: Sanford, L.P., Oak Brook, IL (US)

() Term: 14 Years

(21) Appl. No.: 29/391,467

(22) Filed: May 9, 2011

(51) LOC (9) Cl. 19-06

(52) U.S. Cl. D19/77

(58) Field of Classification Search D8/394,
D8/395, 396; D19/75, 77-85, 99, 100; 24/11 F,
24/11 P, 11 R, 11 CC, 11 CT; 206/214, 224,
206/371; 211/69.1-69.9; 248/316.2, 316.7,

(57) CLAIM

The ornamental design for a eraser and marker holder, as shown and described.

DESCRIPTION

FIG. 1 is a perspective view showing our new design for a eraser and marker holder;

FIG. 2 is a front view of the eraser and marker holder of FIG. 1, the rear view being a mirror image thereof;

FIG. 3 is a side view of the eraser and marker holder of FIG. 1, the opposite side view being a mirror image thereof;

FIG. 4 is a top plan view of the eraser and marker holder of FIG. 1; and,

FIG. 5 is a bottom plan view of the eraser and marker holder of FIG. 1.

The broken lines showing portions of the eraser and marker holder are included for the purpose of illustrating environment and form no part of the claimed design.

1 Claim, 2 Drawing Sheets
